ADJUSTABLE DOOR JACK TABLE

Kenneth H. Walthall, Houston, Tex.

Application March 29, 1956, Serial No. 574,671

4 Claims. (Cl. 144—288)

This invention relates to an adjustable door jack table and more particularly to such a table for use in holding a door in various positions for measurement, work thereon, fitting and hanging.

Today, doors in houses, office buildings, and similar construction are normally held in position for measurement, fitting, and hanging by hand which is fatiguing and requires two men to do the work in most instances. Additionally, because the doors are held in place by hand during measurement there are often inaccuracies in fit.

It is therefore a general object of the present invention to provide an adjustable door jack table which will allow one man to handle a door for measurement, work thereon, fitting, and hanging, which speeds up the work; and which provides mechanical aids in making measurements.

Another object of the present invention is to provide such an adjustable door jack table by which a door may be supported in a longitudinal vertical position and while so supported may be moved vertically, horizontally, and rotated along a vertical axis into position against or adjacent side and top door jambs.

Another object of the present invention is the provision of an adjustable door jack table including jamb finders for indicating excess width and height of doors.

A further object is the provision of an adjustable door jack table including an adjustable straight edge to indicate the line of excess width of a door and assist in guiding a tool cutting off such excess door width.

Yet another object of the present invention is to provide such a door jack table as aforesaid which, after measurements have been made on the door while in a vertical position, permits the door, still supported by the door jack table, to be placed in a horizontal position and from there to side vertical positions for work thereon.

Still another object of the present invention is the provision of a saw guide assembly for use in conjunction with the door jack table for cutting door ends.

And still another object of the present invention is to provide such an adjustable door jack table which is simple and economical to construct and yet dependable in use.

Other objects and advantages will be more apparent from the following description of a preferred example of the invention, given for the purpose of disclosure, and taken in conjunction with the accompanying drawings, where like character references refer to like parts throughout the several views, and where

Fig. 1 is a side view of the adjustable door jack table of the present invention taken along the line 1—1 of Figure 2,

Fig. 2 is an end view of Figure 1,

Fig. 3 is a view similar to Figure 2 except illustrating a door in a side vertical position,

Fig. 4 is a fragmentary perspective view of the gripping and elevating assembly of the present invention,

Fig. 5 is a fragmentary side view illustrating the table assembly of the present invention supporting a door in a longitudinal vertical position,

2

Fig. 6 is a fragmentary perspective view of an adjustable guide member of the adjustable door jack table,

Fig. 7 is a fragmentary sectional plan view of a door and the table assembly in longitudinal vertical position adjacent a doorway.

Fig. 8 is a perspective view of the use of the straight edge of an adjustable guide member and a power plane for trimming a longitudinal edge of a door,

Fig. 9 is a fragmentary side view of the upper portion of a door in place against an upper door jamb illustrating use of a jamb finder,

Fig. 10 is a view along the line of 10—10 of Figure 9,

Fig. 11 is a plan view of the saw guide assembly of the present invention,

Fig. 12 is a fragmentary side view of one end of a door illustrating use of the saw guide assembly with a power saw,

Fig. 13 is a perspective view of a template clamp of the saw guide assembly and

Fig. 14 is a vertical view, partly in section, of the non-marring head of the clamp of Fig. 13.

Referring now to the drawings, and more particularly to Figures 1 and 2, the adjustable door jack table, indicated generally by the numeral 10, includes as a whole the mobile carriage 12 pivotally supporting the table assembly 14 upon which is clamped a door 16. The table assembly 14 is so supported by the carriage 10 that the table assembly 14 with the door 16 clamped thereon may be rotated from the horizontal position of Figure 1 to either side vertical position (see Figure 3) or pivoted into a longitudinal vertical position (see Figure 5) for various purposes which will be made clear later herein.

As best seen in Figures 1, 2 and 3, the carriage 12 has freely pivoted wheels 18 for mobility and has the carriage framework 15 to support one end of the support rod 20, the pivot 22 on the other end of the support rod 20, and the horizontal locking member 24. While the carriage framework 15 may be of various designs, it is preferred to have much of the weight of the table assembly 14 carried well back from the pivot 22 when the table assembly is in the position shown in Figure 5 to eliminate tipping of carriage 12.

As best seen in Figure 1, a table 26 is rigidly secured through a pair of brackets 28 to a pair of horizontally spaced vertical posts 30. The support rod 20, the posts 30, and the brackets 28 are included in the supporting frame of the table assembly 14. Each of these posts 30 is rotatably connected to the support rod 20 at reduced diameter portions 32 by means of sleeves 34 which sleeves 34 and vertical posts 30 have the same external diameter as the external diameter of the unreduced portions of support rod 20. To hold the table 26 in the horizontal position shown in Figure 1, rotation of the sleeves 34 about the reduced portions 32 is releasably prevented by the horizontal portions 36 and 38 respectively of the horizontal locking member 24, each of which horizontal portions lightly contacts the posts 30 (see Figures 2 and 3) on opposite sides and prevent rotation of the sleeves 34 when the posts 30 are in the position shown in Figure 1. This locking member 24 (see Figures 1 and 2) is secured to the carriage framework 15 at the end of the carriage farthest from the pivot 22 and extends forward on one side of the posts 30 to a point above the pivot 22 looping back on the other side of the posts 30 to the carriage framework 15. The horizontal portion 36 is raised close to table 26 to give maximum stability while the horizontal portion 38 is lower to permit manipulation and horizontal movement of crank handle 40 for a purpose which will be made apparent later.

To permit the table assembly 14 to be placed in the side vertical position of Figure 3 after it has been

slid to the right as viewed in Figure 1, the horizontal locking member 24 is curved downwardly and outwardly at 31 from the horizontal portion 36 on each side of the support rod 20 and then upwardly and inwardly at 33 to the horizontal portion 38 forming a forward support 42 (see Figure 1) on each side of the support rod 20. Likewise, the horizontal locking member 24 on each side of the support rod 20 is turned downwardly and outwardly at 35 from the horizontal portion 38 and connected to the rear of the carriage framework 15 to form a rear support 44 on each side of the support rod 20. When in the position shown in Figure 3, the posts 30 rest on these supports 42 and 44 to prevent the door 16 from striking the carriage 12.

From the horizontal position shown in Figure 1 the entire table assembly 14 may be placed into a longitudinal vertical position (see Figure 5) by rotation around the pivot 22. Continued pivoting movement of the table assembly 14 beyond the vertical is prevented because of contacting of support rod 20 against the inner side of the U-shaped end of the horizontal portion 36 of horizontal locking member 24. When in the position shown in Figure 5 the sleeves 34 on the posts 30 permit the table 26 and the door 16 to be pivoted about the support rod 20 to aid in fitting the door 16 into a doorway.

To secure a door 16 to the table assembly 14 and to move the door vertically with respect to the table 26 when in the position shown in Figure 5 there is provided the gripping and elevating assembly 46 (see Figure 4) which includes the pair of parallel door gripping members 48 which are bars each having an upturned jaw 50 on one end in opposed relation to the upturned jaw 50 on the other bar between which the ends of a door 16 are placed and the door gripped. Preferably the portion of the lower jaw 50 contacting the door is about one-eighth to one-fourth of an inch thick for purposes which will be made more apparent later herein. To move the jaws 50 toward or away from one another for gripping or releasing the door 16 there is provided the pinion 52 meshing between adjacent racks 53 on each door gripping member 48 so that rotation of the pinion 52 by the crank handle 40 causes the jaws 50 to move toward or away from one another. To cause the door gripping members 48 to move as a unit vertically when the table assembly 14 is in the position shown in Figure 5 and thus elevate or lower the door 16, there is provided a single pinion 54 meshing with a rack 55 on the outside of one door clamping member 48.

The combination gripping and elevating assembly 46 is located on the bottom side of table 26 (see Figures 1 and 5) with the door gripping members 48 being supported by and slideable through the brackets 28. To prohibit longitudinal movement of pinion 54 relative to table 26 so that the door clamping members 48 will move relative to the table 26 and carry a door 16 with them, the crank handle 56 of pinion 54 is held in position by a bracket 58 secured to the underside of table 26. As pinion 52 and its crank handle 40 must slide along the undersurface of table 26 when the door clamping members 48 are moved as a unit by crank handle 56, there is provided a longitudinally slotted plate bracket 60 (see Figure 5) secured to the underside of table 26 to hold the pinion 52 correctly in place between the racks 53 and permit movement of crank handle 40 along the underside of table 26. Thus, a door 16 may be placed on the table 26 and clamped in position by turning crank handle 40. Thereafter the table assembly 14 may be pivoted about pivot 22 to the longitudinal vertical position of Figure 5 and the door 16 moved vertically by rotation of crank handle 56.

Releasably secured to the table 26 are the adjustable guide members 62 best seen in position in Figure 7 which adjustable guide members 62 are used in determining

the correct width of the door 16 and in planing the door edges to obtain the correct width. One such adjustable guide member 62 is placed on each side of the table 26 and cooperates with the edge of the door 16 on that side of the table.

Each adjustable guide member 62 (see Figure 6) includes a straight edge 64 adjustably secured to the underside of table 26 by a pair of slotted bars 66 and a thumb-screw 68 in each slotted bar. When in position, the straight edges 64 do not reach to the outer edges of the door 16 and are located close to its underside. Releasably secured to each straight edge 64 are a pair of jamb finders 70 having a general U-shape to fit around the edge of a door (see Figure 7) including a pair of legs 71 and 72 with leg 72 being the longer and releasably secured to the straight edge 64. On each leg 71 is a jamb finding lip 73 to fit inside a door side jamb 74 (see Figure 7). In leg 72 opposite the jamb finding lip 73 is a scribe slot 76 through which the door 16 may be marked with a pencil to indicate the location of a side jamb 74.

While the jamb finder 70 may be releasably secured to the straight edge 64 by any of several means, preferably the double wedge assembly illustrated in Figure 6 is used which includes a male wedge 77 on each leg 72 and a complementary female wedge 79 on straight edge 64 with the female wedges 79 all opening toward the upper end of door 16 when in a vertical position so there will be no tendency of the male wedge 77 to fall out. With this double wedge assembly the jamb finders 70 may be removed from straight edge 64 while the door 16 is still held between clamp jaws 50 by knocking the male wedges 77 loose from female wedges 79 and sliding the jamb finders 70 along the straight edge 64 until the end of it is reached.

In use, after the door 16 is clamped in place by the door gripping member 48, the adjustable guide members 62 are slid into position so that the jamb finder lips 73 will fit inside of the side door jamb 74, and the door 16 is raised into the longitudinal vertical position against a doorway. The adjustable guide members 62 are slid outwardly until the jamb finder lips are in the position shown in Figure 7 whereupon the adjustable guide members 62 are secured in position by the thumb screw 68 and scribe marks made on the door.

As the distance from the scribe slot 76 to the straight edge 64 is always constant, the straight edge 64, after the table is rotated to the position shown in Figure 3 and the jamb finders 70 removed, may be used to guide a power plane 78 (see Figure 8) in cutting the edge of the door 16. To do this an adjustable shoe 80, preferably L-shaped in cross section, is secured to the power plane so that the distance between the bottom of the shoe and the bottom of the cutting portion of the power plane 55 is equal to the distance between the scribe mark and the straight edge 64. Thus, the power plane 78 may be run along the edge of the door 16 until the shoe 80 rests on the straight edge 64 whereupon the desired cut has been made.

The jamb finders 70 may also be used to mark excess height of the door 16 in the manner best illustrated in Figure 9 which shows the top of the door 16 held adjacent the top door jamb 82. Before the door 16 is raised into the vertical position a pair of jamb finders 70 are slipped over the top edge of the door 16 and after the door is placed against the doorway the jamb finders 70 are raised by hand until the jamb finder lips 73 strike the top door jamb 82 and the jamb finders 70 are then clamped into position by clamps 84 (see Figure 10). This clamp 84 is preferred as it eliminates marring of the door 16 although other means of securing the jamb finders 70 in position may be used. As best shown in Figure 10, this jamb finder clamp 84 has a cross piece 86 to which are secured a pair of legs 88, on the ends of which legs 88 are cushions 90 bearing against the

surface of door 16. Approximately midway of the cross piece 86 and passing therethrough is a plunger 92 secured by screws (not shown) to leg 72 of the jamb finder 70. Surrounding this plunger 92 is a compression spring 94 bearing against the jamb finder 70 and the cross piece 86. Secured to the end of the plunger 92 projecting through the cross piece 86 is a handle 96 having a cam surface 98 so that when handle 96 is placed in the position shown in Figure 10 the plunger 92 and the portion of the jamb finder 70 secured thereto are drawn away from the door 16 to a slight extent and the leg 71 is forced against the other side of door 16 holding the jamb finder 70 in position. Rotating the handle 96 outwardly until it is perpendicular to the jamb finder 70 will release the jamb finder 70.

The door 16 may be lowered into the position shown in Figure 1 after the jamb finders 70 are locked in the position shown in Figure 9 and a simple straight edge may be used to mark the place of the cut of excessive door height indicated by the jamb finder lip 73.

Referring now to Figure 11 there is illustrated a saw guide assembly indicated generally by the numeral 100 which includes the generally rectangular template 102 having a straight edge 103 to be placed toward the adjacent end of door 16 and a saw guide 104 slidably secured on the template 102. This saw guide assembly 100 is used to aid in cutting off excess height of the door 16 which excess height has been found and indicated by the jamb finder 70 as illustrated in Figure 9 or in some other manner. To secure the template 102 to the door 16 there is provided a pair of template clamps 106 (see Figure 13) each having a wedge shaped head 108 slidably secured in a wedge shaped slot 110 in the template 102 below the outer surface of the template 102 and a non-marring head 112 on an L-shaped arm 114 designed to press against the opposite side of door 16 from that on which the template 102 is placed. Thus when the template is placed into the position shown in Figure 11 it may be secured to door 16 by turning the crank handle 116 on each of the template clamps 106 so that the template 102 is squeezed against the door 16 between the clamp heads 108 and 112 on each template clamp 106. The preferred construction of the non-marring head 112 is shown in Figure 14 and has a non-marring cover such as felt or similar material.

The saw guide 104 is in the shape of a bar having a straight edge 105 toward and parallel to the line of cut of excess door height. It is slidably secured on the surface of the template 102 such as by the screw clamps 118 projecting through the slots 120 in the template 102. As thus constructed, the saw guide may be slid along the surface of template 102 toward and away from the end of door 16 and held in the desired position by tightening on the screw clamps 118.

In use, the saw guide assembly is placed on door 16 after the excess height of the door has been determined such as by the jamb finders 70 and the door has been placed in a horizontal position. The straight edge 103 on the leading side of template 102 is placed in the position desired such as against jamb finder lips 73 when the jamb finders 70 are used as illustrated in Figure 9 and the template 102 is then locked in position by template clamps 106. The jamb finders 70 are removed from the end of door 16 and thereafter a power saw 124 is used as illustrated in Figure 12 by adjusting the saw guide 104 so that the base plate 126 of the power saw 124 bears against the straight edge 105 of the saw guide 104 and places the cutting blade 128 of the power saw 124 at the place of the desired cut. Once the saw guide 104 is locked in position, the power saw 124 may be slid along the top surface of template 102 as the template clamp heads 108 are recessed from this surface. As the straight edge 105 of the saw guide 104 is parallel to the straight edge 103 of the template 102 the blade 128 will then make the correct cuts so long as the operator holds the

base plate 126 of power saw 124 against saw guide 104. As the operator will probably use the same power saw 124 for several doors he can pre-set the saw guide 104 at the desired position on the template 102 and thus the correct cut will be made without further adjustment of the saw guide 104.

In operation of the adjustable door jack table 10, the adjustable guide members 62 will be extended outwardly from the table 26 a sufficient distance to receive a door 16 between the jamb finder lips 73 on opposite sides of the table 26. If the doors 16 are stacked, as is common, the table assembly 14 may be raised to the longitudinal vertical position of Figure 5 and the lower jaw 50 placed at floor level by manipulation of crank handle 56. This lower jaw 50 may be moved under the stacked door 16 by moving the carriage forward and thereafter the door 16 is clamped onto the table assembly 14 by rotation of crank handle 40. The table assembly 14 is then lowered into the horizontal position of Figure 1 where the adjustable guide members 62 are slid inwardly toward the longitudinal edges of the door 16 so that the jamb finder lips 73 will go inside of the side door jambs 74 when the door is raised to a vertical position. Additionally, a pair of jamb finders 70 are placed over the upper end of the door. Thereafter the entire adjustable door jack table 10 is moved on wheels 18 to the desired position and the table assembly 14 is raised to the vertical position (Figure 5) so that the door 16 is held adjacent the doorway in this vertical position. It is to be noted that because the sleeves 34 permit pivoting of the door 16 about the support rod 20 that this adjustable door jack table 10 may be used in narrow spaces such as hallways where the work space is insufficient to permit the carriage 12 to be placed at right angles to the doorway.

After the door 16 has been placed in a vertical position adjacent the doorway, the adjustable guide member 62 on each edge of the door is slid outwardly until the jamb finder lips 73 strike the side door jambs 74 (see Fig. 7) where the adjustable guide members 62 are locked in position by the thumbscrews 68. With the bottom of the door adjusted to the right height from the floor by the rotation of the crank handle 56 the jamb finders 70 on the upper end of the door are slid upwardly to the position shown in Figure 9 so that the jamb finder lips 73 mark the upper jamb 82 of the doorway and such jamb finders 70 are then clamped in position by clamps 84. Thereafter the table assembly 14 is lowered to and locked in the horizontal position (Figure 1).

The jamb finders 70 secured to the straight edges 64 may then be knocked out along the length of the straight edges 64 and the door 16 turned to the side vertical position of Figure 3 where the upper edge is trimmed the desired amount such as by the power plane 78 (Figure 8) with the straight edge 64 guiding and limiting the amount of the cut. Thereafter the table 16 may be turned to the opposite side vertical position for similar trimming of the other edge.

The table is then locked in the horizontal position of Figure 1, the template 102 is placed with its straight edge 103 against the jamb finder lips 73 on the upper end of the door 16 and secured there by clamps 106, and the jamb finders 70 removed from the end of the door. If made necessary by the configuration of power saw 124 or otherwise the clamp jaw 50 nearest that end of the door 16 may be moved out of the way by crank handle 40. A cut is then made along the end of the door cutting off the excess height by placing power saw 124 on the template 102 with the path of the power saw 124 being guided by its base plate 126 bearing against the previously set saw guide 104.

The saw guide assembly 100 may be removed, the door 16 secured by door gripping members 48, and the door 16 then raised to the vertical position again to check the fit. Thereafter the door 16 is lowered to the horizontal position and hinges placed on it. The door 16 is again

raised to the vertical position, fitted in the doorway, and while held in position by the adjustable door jack table 10 has its hinges secured in the doorway. Crank handle 40 is then turned releasing the jaw 50 from the door 16 and the adjustable door jack table 10 is moved away. Because of the thinness of the lower jaw 50 it will permit the door 16 to be hung on its hinges with no more than normal clearance at the floor. The upper jaw 50 need not be so thin as the door 16 is held in position for securing the hinges while the door is open and thus the upper jaw 50 need not pass between the upper end of door 16 and the top door jamb 82.

The present invention, therefore, is well suited to carry out the objects and attain the advantages mentioned, as well as others inherent therein.

While only a single example of the invention has been given for the purpose of illustration, changes in details and rearrangements of parts will suggest themselves to those skilled in the art, especially in regard to the design of the carriage 12, the manner of locking the table 26 in a horizontal position, the jamb finder clamps 84, the template clamps 106 and the like. Accordingly, it is desired to be limited only by the spirit of the invention as defined by the scope of the appended claims.

What is claimed is:

1. An adjustable door jack table comprising, a mobile carriage; and a table assembly supported by said carriage including, a table secured to said carriage by a supporting frame, means associated with said supporting frame and carriage to place said table assembly selectively in a horizontal position or a longitudinal vertical position, and gripping means associated with the table to releasably secure a door on the table assembly and means to move the door vertically including a pair of parallel door gripping members having clamp means on opposite ends thereof, a first rack and pinion assembly associated with said door gripping members adapted to move said door gripping members relative to one another for releasably gripping a door between the clamp means, and a second rack and pinion assembly associated with one such door gripping member adapted to move both said door gripping members and the door held therein as a unit.

2. A door jack table comprising, a mobile carriage; a horizontal support rod supported by and pivotally secured to said carriage for swinging movement in a vertical plane; at least one vertical support post rotatably and slidably connected to said support rod; a table car-

ried by said support post; and a generally horizontal locking member carried by the carriage, said locking member including horizontal portions parallel to a portion of the support rod and adjacent opposite sides of the support post whereby said table may be selectively placed in a horizontal, vertical or a longitudinal vertical position.

3. A door jack table comprising, a mobile carriage; a horizontal support rod supported by and pivotally secured to said carriage for swinging movement in a vertical plane; at least one vertical support post rotatably and slidably connected to said support rod; a table carried by said support post; a generally horizontal locking member carried by the carriage, said locking member including horizontal portions parallel to a portion of the support rod and adjacent opposite sides of the support post whereby said table may be selectively placed in a horizontal, vertical, or a longitudinal vertical position; gripping means associated with the table to releasably secure a door on the table assembly; and means associated with the table to move the door vertically when in a longitudinal vertical position.

4. The door jack table of claim 3 in which the gripping means and the means to move the door vertically include a pair of parallel door gripping members having clamp means on opposite ends thereof, a first rack and pinion assembly associated with said door gripping members adapted to move said door gripping members relative to one another for releasably gripping a door between the clamp means, and a second rack and pinion assembly associated with one such door gripping member adapted to move both said door gripping members and the door held therein as a unit.
